I. PUTNAM

OIL HEATER

Filed May 9, 1922

Fig. 1

UNITED STATES PATENT OFFICE.

ISRAEL PUTNAM, OF ELMIRA, NEW YORK.

OIL HEATER.

Application filed May 9, 1922. Serial No. 559,578.

To all whom it may concern:

Be it known that I, ISRAEL PUTNAM, a citizen of the United States, residing at Elmira, in the county of Chemung and State of New York, have invented certain new and useful Improvements in Oil Heaters; and I do hereby declare the following to be a full, clear, and exact description of the same, reference being had to the accompanying drawings, forming a part of this specification, and to the reference numerals marked thereon.

My present invention relates to heating appliances and more particularly to oil stoves of the simple type used for heating poultry houses and for warming the water provided for the fowl to prevent it from freezing in extreme weather, and it has for its object to provide an improved stove of this character embodying certain provisions against the danger of explosions due to accumulations of vapor from the oil fuel, while also operating to prevent accumulations of moisture, particularly water of condensation, from interfering with combustion. To these and other ends the invention consists in certain improvements and combinations of parts, all as will be hereinafter more fully described, the novel features being pointed out in the claim at the end of the specification.

In the drawings:

Figure 1 is a central vertical section through an oil heater constructed in accordance with and illustrating one embodiment of my invention.

Figure 2 is an enlarged fragmentary vertical section of the lower end of the burner tube.

Figure 3 is a bottom view of the burner tube.

Figure 4 is a view similar to Figure 2, of a slightly modified construction; and

Figure 5 is a bottom view of the modified form of Figure 4.

I have illustrated a stove or heater of known general construction embodying a closed reservoir 1 having a top 2 over which engages in telescopic relationship a cover 3, the top of which 4 is spaced above the top 2 of the reservoir, and is preferably flat so that a crock or similar drinking receptacle can be rested and maintained thereon. The side walls of the cover are provided with suitable upper and lower vents and draft openings 5 and 6. Both of the

above parts are preferably cylindrical and a bead 7 on the lower rim of the reservoir 1 projects downwardly sufficiently to provide a flat bottom for the stove as a whole. 60

Depending from the top 2 of the reservoir, at its center, and through which it projects, is a burner tube 8 the upper end of which is entirely open, as indicated at 9, and raised slightly above the top 2. It 65 may be soldered in place, or, at any rate, sealed to the reservoir at this point. Within the tube is a suitably bent resilient wire yoke 10 constituting a wick holder and adapted to be inserted and withdrawn 70 through the mouth of the tube and to maintain itself in any desired elevation to which it may be adjusted. One upwardly extending arm of the yoke, shorter than the other, is coiled or otherwise fitted as at 11, to hold the wick 12, while the other arm projects from the tube at all times and is bent to form a handle 13. The wick 12 is much smaller than the tube in diameter 75 and is held away from the walls thereof by the wick holder, so that the air required for combustion can pass between the wick and tube and burn the vapors issuing at the mouth of the latter, besides supplying plenty of oxygen for full combustion on the wick 80 itself. This prevents the wick from fouling and from adhering to its tube through accumulations of carbon at the mouth of the tube. To raise or lower the wick, it is necessary only to slide the holder 10 up and 85 down by means of the handle.

The lower end of the burner or wick tube 8 as indicated at 14 is spaced above the bottom 15 of the reservoir and is foraminous, being pierced by a plurality of small openings indicated at 16 in Figs. 2 and 3. Also, the bottom 15 of the reservoir is preferably slightly concaved or dished. There are several reasons for this arrangement, in the practice of my invention. More or less 90 water of condensation is generated within the burner tube 8 and descends first to the bottom of the tube and then through the opening 16 to the bottom of the reservoir, at 15, where, with the depressed bottom, it collects in a low pool at the center. If the bottom 14 of the tube were close to this bottom 15 of the reservoir, the stove would often be rendered inoperative due to these accumulations of water freezing and sealing the lower end of the tube. If, on the other hand, 100 the level of the body of oil indicated at 17 in

Fig. 1 drops below the lower end of the burner tube, there is danger of fire or explosion, due to the oily vapors that collect within the reservoir becoming ignited from the flame in the tube. The foraminous bottom 14, which I provide, prevents such combustion on the principle of a miner's lamp, while at the same time giving ample passage to the oil feed into the tube and to the escape of water of condensation originating in the tube. I have found that without such an arrangement the water is apt to freeze, or otherwise clog, the bottom of the tube and prevent the oil from flowing there-

5
10
15 in.

In Figs. 1, 2 and 3, I have shown the tube 8 constructed of a single piece of sheet metal with apertures 16 punched in the end or bottom thereof. The tube may, however, also 20 be made as shown in Figs. 4 and 5, in which the tubular body portion 8^a has not a solid bottom or end but is covered with wire gauze, as indicated at 14^a and which is held 25 in place by a sleeve or collar 18 on the exterior of the tube. The meshes of the gauze provide the equivalent of perforations 16 of the other form.

The stove constructed as above described is perfectly safe to leave without attention in a poultry house for long periods during 30 which it will burn continuously on one filling, and often without more than the most infrequent adjustments of the wick.

The reservoir 2 is filled in the ordinary manner through a neck 21 at one side closed 35 by a cap 22 having a small vent 23 therein.

I claim as my invention:

In an oil lamp, the combination with a sealed reservoir, of a wick tube extending downwardly therein from the top wall of 40 the reservoir and having a bottom closed by a foraminous diaphragm including a multiplicity of fine openings adapted to both allow water to instantly escape from the tube and oil to flow freely into the same, the bottom of the tube being spaced from the bottom of the reservoir, a wick in the tube, and means for supporting the wick in spaced 45 relationship to the walls of the tube, so that an air space is left around the wick from the mouth of the tube down to the level of the oil therein.

ISRAEL PUTNAM.
